FRANK J. SCHLEICHER, OF UNIVERSITY CITY, MISSOURI.

DESIGN FOR A BOX.

Application filed June 8, 1929. Serial No. 31,598. Term of patent 14 years.

To all whom it may concern:

Be it known that I, FRANK J. SCHLEICHER, a citizen of the United States, residing at University City, St. Louis County, State of Missouri, have invented a new, original, and ornamental Design for Boxes, substantially as shown in the accompanying drawing.

In the drawings—

Fig. 1 is a perspective view of a box showing my new design.

Fig. 2 is a perspective view showing the box from another position.

The statuette 1 is mounted on a part 2 occupying a central position upon the top 3 of the box, the linings for colors indicating that

the parts 2 and 3 are distinctively colored. Around the part 3 is a defined marginal area 4 that is distinctively colored from said part 3, and around the part 4 there is a horizontal area 5 that is distinctively colored from the part 4. The side walls 6 of the box are distinctively colored from the upper marginal portion 7 and lower projecting portion 8 which has a vertical edge 9 distinctively colored from a projecting base 10.

I claim:

The ornamental design for a box, substantially as shown and described.

FRANK J. SCHLEICHER.
